DESIGN FOR A TEMPLET FOR DRAWING ELLIPSES

Adrian J. Gilardi, Seattle, Wash.

Application May 3, 1944, Serial No. 113,452

Term of patent 14 years

(Cl. D52—1)

To all whom it may concern:

Be it known that I, Adrian J. Gilardi, a citizen of the United States, residing at Seattle, in the County of King and State of Washington, have invented a new, original, and ornamental Design for a Templet for Drawing Ellipses, of which the following is a specification, reference being had to the accompanying drawing, forming part thereof.

Fig. 1 is a plan view of a templet for drawing ellipses, showing my new design; and

Fig. 2 is a sectional view taken on the line 2—2 in Fig. 1.

I claim:

The ornamental design for a templet for drawing ellipses, substantially as shown.

ADRIAN J. GILARDI.
